ROBERT GRISTY Inventor

By *Richard B. Owen* Attorney

Patented Nov. 28, 1922.

UNITED STATES PATENT OFFICE.

ROBERT GRISTY, OF DETROIT, MICHIGAN.

SASH LOCK.

Application filed April 17, 1922. Serial No. 553,772.

To all whom it may concern:

Be it known that I, ROBERT GRISTY, a citizen of the United States, residing at Detroit, in the county of Wayne and State of Michigan, have invented certain new and useful improvements in Sash Locks, of which the following is a specification.

The present invention relates to improvements in sash locks and has for its principal object to improve the construction of devices of this nature by providing a simple, inexpensive, and efficient structure one possessing strength and durability and adapted to be readily applied to a window so as to be capable of securely locking a sash in its closed position and at various adjustments.

Another object of the invention is to provide means of this nature whereby the upper sash may be locked in varying adjusted positions in relation to each other.

Another object of the invention is to secure greater safety and convenience and to provide a structure which may be readily locked or unlocked.

With these and other objects in view, the invention consists in the construction and novel combination of parts hereinafter fully described, illustrated in the accompanying drawing, and hereinafter claimed; it being understood that various changes in the form, proportion, size and minor details of construction, within the scope of the invention as claimed, may be resorted to without departing from the spirit or sacrificing any of the advantages of the invention.

In the drawing:—

Figure 1 is a perspective of a sash lock constructed in accordance with my invention and shown applied to a portion of a window.

Figure 2 is an elevation thereof.

Figure 3 is a similar view showing the sashes in adjusted positions.

Figure 4 is an edge elevation thereof showing the sashes in adjusted positions.

Figure 5 is a perspective of a pivoted hook used in conjunction with this invention.

Figure 6 is a perspective of a pivoted locking member, and

Figure 7 is a perspective of the keeper bar adapted to be attached to the lower sash.

Referring to the drawing in detail it will be seen that the window frame 1 is of conventional construction having slidably mounted therein the lower sash 2 and upper sash 3. The keeper bar 4 is provided with a

plurality of transversely extending notches in one of its side edges while its other side edge is provided with a pair of end apertured ears 6 and an intermediate apertured ear 7 extending in an opposite direction to the end ears 6. These ears 6 and 7 extend at right angles from the keeper bar 4. The ears 6 and 7 are adapted to be fixed to the lower sash 2 by screws or other similar devices and is situated so as to extend vertically therewith and so that its upper end terminates flush with the upper end of the sash. The locking arm 9 is provided with an angularly extending apertured ear 10 having a notch 11 therein and this ear 10 is pivoted to the window frame adjacent the top of the lower sash 2 so that the same may be pivoted and engaged with the notches 5 of the keeper bar 4 and hold the lower sash 2 in raised adjusted positions. When the sash 2 is closed the arm 9 is adapted to engage the top of the keeper bar 4 as shown to advantage in Figure 1. When the sash 2 is in a raised position, any instrument may be used for engagement with the notch 11 of the locking arm 9 so that the arm may be pivoted out of engagement with one of the notches 5.

A keeper bar 13 is attached to the upper sash adjacent the window pane and is formed in two pivoted sections. The main section 14 is provided with a plurality of notches 15 and with apertured ears 16 which are secured to the sash 3 as shown to advantage in Figure 1. The auxiliary section 17 of the keeper bar is pivoted to the main section 14 at 18 and is also provided with a plurality of notches 19 similar to the notches 15 and this section 17 is retained in raised position by the pivoted hook 20 mounted at 21 on the sash 3. A locking arm 23 is pivoted at 24 on the top of the lower sash 2 and is adapted to engage the notches 15 and 19 of the keeper bar 13 whereby the sashes 2 and 3 may be held in adjusted position when desired. When the auxiliary or upper section 17 of the keeper bar 13 is not in use it is allowed to pivot to the position shown in Figures 3 and 4 whereby the notches 19 will register with the notches 15 and hold the locking arm 23 within these notches. This arrangement is preferably used when the sashes are only slightly adjusted in relation to each other and when it would be rather easy for an unauthorized person to reach the locking arm 23. However when the sashes are open or adjusted to a considerable extent the aux-

iliary section 17 is used in its extended position and the locking arm 23 engages one of the notches thereof.

Having thus described my invention what I claim as new is:—

- 5 1. In combination, a window frame, a pair of sashes mounted in the window frame, a keeper bar formed in two sections pivoted together at their adjacent ends, each of said 10 sections provided at intervals with marginal notches, means for holding the sections in extended positions, means for attaching one of the sections to one of the window sashes, and a locking arm on the other sash for engagement with the notches.

- 15 2. In combination, a window frame, a pair of sashes disposed in the window frame, a keeper bar mounted on one of the sashes and formed in a pair of pivoted sections, each 20 section provided at intervals with marginal notches, a pivoted hook member on the last sash engageable with the pivoted extension of the keeper bar for holding it in an extended position, a locking arm pivoted on the other sash for engagement with the notches thereof, and means for locking said latter sash in engagement with the window frame.

tended position, and a locking arm pivoted on the other sash for engagement with the notches thereof.

3. In combination, a window frame, a pair of sashes disposed in the window frame, a keeper bar mounted on one of the sashes and formed in a pair of pivoted sections, each 30 section provided at intervals with marginal notches, a pivoted hook member on the last sash engageable with the pivoted extension of the keeper bar for holding it in an extended position, a locking arm pivoted on the other sash for engagement with the notches thereof, and means for locking said latter sash in engagement with the window frame.

In testimony whereof I affix my signature 40 in presence of two witnesses.

ROBERT GRISTY.
